UNITED STATES PATENT OFFICE.

LEWIS J. EVANS, OF SCRANTON, PENNSYLVANIA.

ELEVATING DEVICE.

1,150,752.

Specification of Letters Patent. Patented Aug. 17, 1915.

Application filed May 4, 1914. Serial No. 836,318.

To all whom it may concern:

Be it known that I, LEWIS J. EVANS, citizen of the United States, residing at Scranton, Pennsylvania, have invented certain new and useful Improvements in Elevating Devices, of which the following is a specification.

The present invention relates to elevating devices, and pertains more particularly to such a one as is adapted to be used in conjunction with a heater or furnace to facilitate removing and replacing the ash cans which are normally located beneath the floor of the furnace room in a well or pit directly under the fire box of the heater.

One object of the present invention is to provide an elevating device for ash cans which can be contained and operated within a comparatively small pit formed below the furnace floor and in proximity to the heater.

A further object of the invention consists in providing an elevating device for ash cans of the class above described in which a movable platform is normally maintained within the lower part of the pit and in a position such that the can resting upon it will be directly under the heater, and also to provide means by which this platform may be first swung outwardly from the projecting edge of the heater and then elevated to the surface of the furnace floor, during all of which operations the platform will be maintained in a horizontal position.

The invention further contemplates providing a single, rigid shaft located within the pit or well, upon which the platform is moved up and down, and operating means suitably connected with this shaft adapted to be hinged in such manner as to extend at an angle out of the well when the device is being operated, and to be folded within the well when the device is not in use. As disclosed in my prior Letters Patent #1,077,691, granted to me November 4, 1913, a hinged cover is provided for the well or pit adapted, when the device is not in use, to close flush with the surface of the cellar floor.

A collapsible chute for discharging the ashes from the fire box of the furnace into the can when the latter is in its lowermost position is provided similar to that disclosed in my copending application Serial Number 767,676.

With these and other objects in view, the invention consists in the novel features of

construction and combination and arrangement of parts hereinafter described and particularly defined by the appended claims.

In the drawings Figure 1 is a plan view of one embodiment of the invention; Fig. 2 is a longitudinal vertical section taken on the line 2-2 of Fig. 1, with the can and platform shown in elevated position in dotted lines; Fig. 3 is a transverse vertical section taken on line 3-3 of Fig. 1 showing the can in elevation in its lower position; Fig. 4 is a detail plan view of the movable platform; Fig. 5 is an enlarged detail view of the lower shaft bearing.

Referring to the drawings, the pit 1 is formed below the level 2 of the furnace floor of a depth sufficiently greater than the height of the ash can, and is shaped at its ends with semi-circular walls conforming to the outer shape of the cans.

The fire box of the furnace is shown at 3, projecting slightly over the rear edge of the well or pit 1.

Around the upper perimeter of the well 80 a frame 4 is constructed of bars of angle iron, one edge of which is countersunk flush with the concrete floor 2, while the other edge at right angles thereto extends within the walls of the pit or well, forming an inner 85 lining around its upper edge.

In order to form as compact a structure as possible, the pit is made of the design illustrated in Fig. 1, and its length from front to back is less than twice the diameter 90 of the ash can.

A vertical shaft 5 is supported by a bracket 6 secured to the metal framework at the upper edge of the pit, and at a point approximately midway of its length. At its 95 lower end this shaft is supported in a metal socket 7* sunk in the concrete of the lower wall of the pit. The shaft 5 is provided with a screw thread. The can-receiving platform 7 is circular in shape, and is provided on its under side with a reinforcing web piece 8, having formed at its outer edge a projecting bracket sleeve 9 which is internally screw-threaded, and through which the shaft 5 passes. The lower edge of the bracket 9 rests, when the platform is in its lowest position, on a collar 25 rigidly secured to the shaft 5. Thus, a gripping action is provided so as to insure the turning of the platform and shaft together when the former is swung under or out from the edge 100 of the furnace.

An operating shaft 10 provided with a handle 11 is connected with the upper end of the shaft 5 by means of a universal joint connection 12.

5 A pair of lugs or fingers 13 is formed in the upper edge of the frame 4, and serve as guide means for the shaft 10 when it is in its operating position, and extends from out the well or pit.

10 A small semi-circular guard plate 13^a is pivotally secured to one of the lugs 13 and is adapted to be locked in position around the rod 10 by a pin 13^b carried in a lug 13^c and adapted to enter a slot or recess formed in its edge. By withdrawing the pin the plate 13^a may be swung about its pivot and the arm 10 folded over into the pit 1.

15 A vertical double box shaft 14 is arranged at the front of the pit, being secured by bolts 20 to the upper framework, and having its lower end embedded in the concrete floor.

20 A small anti-frictional roller 15 is secured at the edge of the platform 7 at a point diametrically opposite the hinged bracket 9. 25 This roller is adapted to contact with one side of the box shaft 14 to limit the outward swinging movement of the platform, and to travel within the box shaft 14 as the platform is being elevated. This shaft is 30 shorter on one side allowing the roller to pass under and come in contact with the opposite side. The metal lug 16 is also provided extending from the edge of the circular platform 7, and is adapted to contact 35 with the stop 17 suitably located near the lower part of the rear wall of the pit.

40 A collapsible chute 18 is formed in the upper permanent cover plate 19, which is fastened by means of bolts over the rear end of the pit. This chute is located directly beneath the fire box 3 of the furnace, and is 45 opened and closed by means of a chain 20 fastened to a button 21 extending through a plate 22 in the cover portion 19. The chute, when open, directs the ashes cleared from the fire box of the furnace into the can carried on the platform. The hinged metal cover plate 23 provided with a handle not shown, is secured to the frame 2 and is 50 adapted, when closed, to lie flush with the furnace floor.

55 The operation of my device is as follows: Assuming the platform 7 to be in its lower position in the rear part of the pit 1, directly under the projecting edge of the heater and carrying on it an empty ash can C, the can is filled with ashes falling through the collapsible chute 18, which is normally open. The chute is then closed by 60 means of the chain 20 in order to prevent any further ashes from falling into the pit; the main cover 22 is opened, and the operating shaft 10 swung about its universal joint so that the handle 11 is in a position readily accessible to one standing in the furnace

room beside the pit. The guard plate 13^a is then locked in place by the pin 13^b. Upon turning the handle to the right the shaft 5 will be rotated in a corresponding direction, which will cause the platform 7 to swing forward until the roller 15 contacts with the side of the vertical box shaft 14, then upon continued turning of the handle the platform will rise, due to the threaded connection between the shaft 5 and the bracket 75 sleeve 9. When the platform has reached its highest position, the bracket sleeve 9 will contact with the bracket 6, and the platform will then be on a level with the surface of the furnace room floor so that the can can 80 be removed readily and the ashes dumped. The empty can is then placed on the platform and the handle turned to the left, when the reverse of the operation just described will take place. The platform will be lowered by the shaft 5, and then will be swung about the bracket sleeve 9 as a pivot into the rear portion of the pit until the lug 16 contacts with the stop 17, whereupon the empty can will be in position to receive the ashes 90 from the furnace.

95 A hook 24 is fastened by a chain at some convenient place on the furnace front and is hooked onto the handle 11 to hold same in locked position when the can and platform are elevated.

I claim as my invention:

1. In combination with a well or pit, a horizontally disposed platform pivotally mounted in proximity with the bottom of said well, means operatively connected with said platform for swinging same horizontally about its pivot and elevating it to the upper level of the well, substantially as described. 100

105 2. In combination with a well or pit, a vertical shaft therein, a horizontally disposed platform pivotally connected to said shaft, operating means coupled to said shaft adapted to swing said platform horizontally about said shaft and to raise or lower it vertically along said shaft, substantially as described. 110

115 3. In combination with a well or pit, a rotatable vertical shaft supported therein, a horizontally disposed platform having pivotal connection with said shaft, operating means coupled with said shaft including a handle, adapted when turned in one direction to swing said platform about its pivot in a horizontal plane and upon further movement in the same direction to elevate said platform along said shaft, substantially as described. 120

125 4. In combination with a well formed below and in proximity with a heater, a movable platform adapted to carry an ash can, a rotatable vertical shaft supported within said well and having screw threaded connection with said platform, means for 130

rotating said shaft to swing said platform in a horizontal plane and to raise or lower the platform at will, substantially as described.

5. In combination with a well formed below and in proximity with a heater, a movable platform adapted to carry an ash can, a rotatable vertical shaft supported within said well, a bracket arm formed on said 10 platform and screw threaded on said shaft, operating means coupled with the upper end of said shaft for rotating same to swing said platform in a horizontal plane and to raise or lower it at will, substantially as described.

15. 6. In combination with a well formed below and in proximity with a heater, a movable platform therein adapted to carry an ash can and normally located directly beneath said heater at the bottom of said well, means for swinging said platform in a horizontal plane from beneath said heater and means for elevating said platform to the upper level of said well, comprising a vertical rotatable shaft within said well having screw threaded connection with said platform, and operating mechanism suit-

ably coupled with the upper end of said shaft, substantially as described.

7. In combination with a well formed below and in proximity with a heater, a movable platform therein adapted to carry an ash can, and normally located at the bottom of said well in a position directly under said heater, means for swinging said platform in a horizontal plane from beneath said heater and means for elevating said platform to the upper level of said well, comprising a vertical rotatable shaft within said well having screw threaded connection 30 with said platform and an operating mechanism comprising a second shaft provided with a handle and coupled with the upper end of said shaft, said operating mechanism being adapted, when in use, to extend out 35 of said well at an angle and when the device is not in use to be folded within said well, substantially as described.

In testimony whereof, I affix my signature in presence of two witnesses.

LEWIS J. EVANS.
